COMBINATION BURNER

James A. Creighton, Hamburg, N. Y., assignor to
Bethlehem Steel Company, a corporation of
Pennsylvania

Application July 12, 1940, Serial No. 345,092

2 Claims. (CL 158—73)

This invention relates to combination burners for introducing liquid and gaseous fuels into furnaces, and relates more particularly to burners for introducing fuels into high-temperature furnaces, such as open-hearth furnaces used in the production of steel, and also other high-temperature furnaces, in which it is necessary to provide water- or other liquid-cooled jackets through which the fuel pipes are introduced into the heating or melting chambers.

Heretofore when burners have been used for heating furnaces of this type, it has been the usual practice to have a burner with a single jet at each end of the furnace employing one, or an appropriate combination, of various gas and liquid fuels.

My invention differs from the conventional burner in that there are two oil or liquid fuel injection pipes, one located on either side of a combination gas and oil or liquid fuel pipe, all enclosed in a common water-cooled jacket, and the entire burner is located in the furnace in a flat position with all the fuel pipes on the same horizontal center line. I also introduce steam into the burner around each of the oil or liquid fuel injection pipes, whereby combustion is greatly stimulated and a much more intense heat is produced.

Another advantage of a burner of this type is that such a burner gives a better flexibility for the distribution of flame across the hearth of the furnace; lowers the flame with relation to the roof; provides more complete atomization of fuel; and the general operation of the furnaces equipped with this style burner is greatly improved in numerous respects.

Other objects of my invention will hereinafter appear.

Having thus given a general description of the advantages of my invention, I will now in order to make the same more clear, refer to the annexed two sheets of drawings forming a part of this specification and in which like characters of reference indicate like parts.

Figure 1 is a longitudinal section taken through the upper portion of an open-hearth furnace showing a burner at each end of the furnace;

Figure 2 is a horizontal section through the rear end of the burner and showing the pipe connections for supplying the oil, gas and steam to the burner;

Figure 3 is a horizontal longitudinal section through the burner taken on the line 3—3 of

Figure 5 with the pipe connections shown in elevation;

Figure 4 is a vertical longitudinal section taken on the line 4—4 of Figure 5; and

Figure 5 is a vertical transverse section taken on the line 5—5 of Figure 4.

Referring now to the various characters of reference on the drawings, the numeral 1 designates the upper portion of a regenerative basic 10 open-hearth steel furnace, 2 its roof, 3 the hearth, and 4 the bath. Each end of the furnace is provided with the usual air uptakes 5 communicating with the regenerators (not shown) through which the heated air is received for the 15 burner in operation or the waste gases are discharged from the combustion chamber. An opening 6 is formed in each end of the furnace for the reception of a burner 1 which preferably has a hood 8 of refractory material extending 20 over the burner.

As each of these burners is of the same construction a description of one will apply to both.

The burner has an outer casing 9 formed of a standard pipe which is flattened to form an oval tubular shaped member as indicated in Figure 5, and closed at the front and rear ends by means of plates 10 and 11, respectively, to form a water-jacket for the circulation of cooling water which is supplied through the forwardly projecting 25 water inlet pipe 12 feeding into the transverse pipe 12a welded thereto. Each end of said transverse pipe 12a is closed by welded round plate 12b, and is supported on the oval sides of the water-jacket near the front end and slightly 30 above the bottom on a horizontal plane. Welded to said transverse pipe 12a are three forwardly projecting nipples or nozzles 12c, one being directly beneath each one of the subsequently described burner tubes 14, 25 and 26 for 35 individually cooling each tube. The warm spent water rises to the top and rear of the water-jacket and is there withdrawn through outlet pipe 13.

Extending through the middle portion of the 40 water-jacket in parallel relation to the side wall is a large central tube 14 which extends through the end plates 10 and 11 and is welded thereto. The rear end of the tube 14 extends beyond the rear end plate 11 and is threaded to receive a T-fitting 15 which is coupled to receive a coke-oven or fuel gas supply pipe 16 and a reducer-fitting 17, which last is also threaded to receive T-fitting 18. T-fitting 18 in turn is coupled to steam inlet pipe 19 and threaded to receive a stuffing box 20 adapted to support the rear end

of oil burner pipe 21. Said oil burner pipe 21 extends through the gas and steam pipe 14, being supported centrally therein near the front end by means of spider 22, and also extends through the stuffing-box 20 to couple through an L-fitting 23 to an oil supply pipe 24.

Parallel to and on the same horizontal plane with the central tube 14, but separate from and on opposite sides thereof are tubes 25 and 26, which also extend through the end plates 10 and 11 and are welded thereto. The rear ends of said tubes 25 and 26 likewise extend beyond the rear end plate 11 and are threaded to receive couplings 27 and 28, which in turn are threaded to receive nipples 29 and 30. Said nipples are coupled to T-fittings 31 and 32, which couple to steam inlet pipes 33 and 34. T-fittings 31 and 32 are provided with stuffing-boxes 35 and 36, respectively, which support the rear ends of oil burner pipes 37 and 38. These oil burner pipes 37 and 38 extend centrally through the tubes 25 and 26, and their rear ends extend through the stuffing-boxes 35 and 36 and are threaded for L-fittings 39 and 40, which couple to oil supply pipes 41 and 42. The said inner oil burner pipes 37 and 38 are held centrally within the tubes 25 and 26 by means of spiders 43 and 44.

For illustration, I have described my invention as a combination oil, steam and gas burner particularly adapted for use in an open-hearth furnace, but I wish it understood that it may be used with other kinds of furnaces equally as well, and that tar or other liquid fuel may be substituted for oil if desired.

Although I have shown and described this invention in considerable detail, I do not wish to be limited strictly to the exact and specific details shown and described, but may use such substitutions, modifications or equivalents thereof as are embraced within the scope of the invention or as pointed out in the claims.

Having thus described my invention, what I

claim as new and desire to secure by Letters Patent is:

1. A burner unit for a regenerative open hearth steel furnace, comprising a plurality of tubes arranged horizontally in parallel alignment to each other, means for supplying steam to the tubes, a smaller liquid fuel pipe extending through each of said tubes and secured therein, means for supplying liquid fuel to said smaller pipes, an oval outer casing surrounding the tubes, end plates welded to front and rear ends of said tubes and outer casing, a forwardly extending T-shaped water inlet pipe in the bottom part of the outer casing, a plurality of nipples projecting from the transverse pipe and directed toward the front end plate, means for supplying cooling water through the water inlet pipe and nipples, and means for discharging the spent water.

2. A burner unit for a regenerative open hearth steel furnace, comprising a pair of tubes arranged horizontally in parallel relation to each other at opposite sides of the burner unit, a tube of larger diameter disposed centrally of the burner unit in evenly spaced parallel alignment between said pair of tubes, a liquid fuel burner pipe mounted in each of the tubes, means for supplying liquid fuel to each liquid fuel burner pipe, means for injecting steam into each of the tubes around the liquid fuel burner pipes, means for introducing gas into the central tube for mixing with the steam therein, an oval outer casing forming a water-jacket surrounding the tubes, an end plate secured at each end of the casing supporting an end of each tube, a forwardly projecting water inlet pipe welded to the rear end plate, means for supplying water to the water inlet pipe, a transverse horizontal pipe with closed ends welded to said water inlet pipe, a nipple projecting from said transverse pipe directly beneath each tube for cooling the tube, and an outlet pipe for discharging spent water from the water-jacket.

JAMES A. CREIGHTON.
